US00D814626S

(12) **United States Design Patent** (10) Patent No.: **US D814,626 S**
(45) Date of Patent: ** Apr. 3, 2018

(54) **HEAT SPREADER**

(71) Applicant: **GraffTech International Holdings Inc.**,
Brooklyn Heights, OH (US)

(72) Inventor: **Martin D. Smalc**, Parma, OH (US)

(73) Assignee: **NeoGraf Solutions, LLC**, Lakewood,
OH (US)

(**) Term: **15 Years**

(21) Appl. No.: **29/562,390**

(22) Filed: **Apr. 25, 2016**

(51) LOC (11) Cl. **23-02**

(52) U.S. Cl.

USPC **D23/419**

(58) **Field of Classification Search**

USPC D23/387, 354, 386, 393, 419; D13/179
CPC .. F24F 7/00; F24F 7/02; A41D 13/005; H05B
3/02

(57) **CLAIM**

The ornamental design for a heat spreader, as shown and described.

DESCRIPTION

FIG. 1 is a front view of a heat spreader;
FIG. 2 is a front view of the heat spreader shown in FIG. 1;
FIG. 3 is a back view of the heat spreader shown in FIG. 1;
FIG. 4 is a back view of the heat spreader shown in FIG. 1;
FIG. 5 is a front view of heat spreader shown in FIG. 1;
FIG. 6 is a left side view of the heat spreader shown in FIG. 1;

1;
FIG. 7 is a right side view of the heat spreader shown in FIG. 1;

FIG. 8 is a top view of the heat spreader shown in FIG. 1;
and,

FIG. 9 is a bottom view of the heat spreader shown in FIG. 1.
